ATTORNEY:

UNITED STATES PATENT OFFICE.

AUGUSTUS E. BEH AND ESTELLA BEH, OF WEST SOLVAY, NEW YORK.

MUSIC-LEAF TURNER.

No. 853,571.

Specification of Letters Patent.

Patented May 14, 1907.

Application filed August 29, 1906. Serial No. 332,495.

To all whom it may concern:

Be it known that we, AUGUSTUS E. BEH and ESTELLA BEH, of West Solvay, in the county of Onondaga, in the State of New York, have jointly invented new and useful Improvements in Music-Leaf Turners, of which the following, taken in connection with the accompanying drawings, is a full, clear, and exact description.

10 This invention relates to certain improvements in leaf-turners, and is especially adapted for supporting and turning the leaves of sheet music.

15 My main object is to simplify and quicken the operation of turning the leaves, one at a time, without in any way disarranging, or displacing the other leaves. In other words, I have sought to provide a simple and practical self-retracting manual by which the leaf-20 turning arm may be thrown from one position to the other by a single stroke of the finger similar to that required for operating the key of a piano or similar musical instrument, and at the same time to leave the arms free to 25 be rocked by hand irrespective of their operating manuals.

30 A further object is to provide adjustable fingers for engaging in the lower and upper ends of the fold or junction of the music-sheets so as to firmly hold a single sheet or a plurality of sheets with the same degree of efficiency.

35 Another object is to provide for the further adjustment of one of said fingers to permit the leaves or book to be readily withdrawn from its supporting frame and leaf-turning arms.

40 Other more specific objects and uses will be brought out in the following description.

45 In the drawings—Figure 1 is a front elevation of my improved leaf-turner. Fig. 2 is a sectional view taken on line 2—2, Fig. 1. Figs. 3 and 4, are enlarged sectional views taken respectively on lines 3—3, and 4—4, Fig. 1.

50 A skeleton frame —1— of wood or other suitable material is adapted to be supported in the usual manner upon the ordinary leaf-rest of the musical instrument, and is provided with a bottom rail having a forwardly projecting ledge 2 upon which the lower edge of the music-sheets are adapted to rest. This frame is provided with a central vertical bar projecting some distance below the bottom rail or ledge —2, and upon this lower 55 projecting end is mounted a hollow head or

housing —3— for receiving and supporting a pair of rock-shafts —4— and separate pairs of self-retracting plungers or manuals —5—, one pair for each of the rock-shafts —4—. 60 These rock-shafts extend entirely through the housing or head —3— from top to bottom and are journaled in the upper and lower sides, the upper ends being provided with laterally projecting arms —6— adapted to 65 swing in a substantially horizontal plane just above the ledge —2—, said rock-shafts being located equidistant from and at opposite sides of the central upright bar at the longitudinal center of the frame —1—. 70

The arms —6— are adapted to receive and support the leaves which are to be turned, and preferably consist of wires of comparatively small gage bent into the form of a rectangular frame except that a portion of 75 the lower horizontal wire of each arm is looped upwardly some distance above the upper horizontal bar, and is offset forwardly in a plane a slight distance from the remaining portions of the arm to form a seat and retaining finger for the music-sheet, said loop or retaining finger being designated by the numeral —7—.

80 The lower ends of the rock-shafts —4— project some distance below the bottom of the housing —3— and are provided with suitable hand-pieces, such as knobs —8—, adapted to be engaged by the operator to rock the shafts independently to throw the arms —6— and music-sheet which may be 85 engaged therewith on opposite sides of the swinging axis of said arms, or in other words, to turn the leaves from one side to the other. These rock-shafts are held against axial movement by their respective knobs —8— 90 and suitable collars —9— which engage opposite sides of the head or housing —3—. As a further means for operating the arm —6— to turn the leaves more expeditiously, I provide each shaft —4— with an offset or crank-arm —10— having opposite working faces —11—, each adapted to be engaged by one of its operating plungers —5— which are located at opposite sides of the axis of the rock-shaft, and are adapted to move transversely 100 thereto in the path of the movement of the offset or crank-arm —10—.

105 The plungers —5— are guided in suitable bearings —12—, and project outwardly some distance through the front side of the 110 housing —3—, the outer ends being provided with finger-keys —13—, while their inner

ends are threaded and provided with ball-shape nuts —14— which engage the rear ends of the bearings 12— to limit the outward movement of the plungers which is effected by suitable retracting springs —15—.

The ball surfaces of the nuts 14— constitute abutments against which the crank-arms 10— rest when the arms —6— are shifted from one position or the other; that is, the operating faces —11— swing alternately into and out of engagement with the abutments 14— as the leaf-supporting arms —6— are rocked in reverse directions.

It is now clear that by depressing one of the plungers which may be engaged by the crank-arm —10—, the rock-shaft to which said crank-arm is secured will be rotated and its leaf-turning arm —6— positively shifted through practically a quarter of a revolution, while the momentum imparted to said rock-shaft and arm will carry the latter through the remainder of its movement, or substantially another quarter of its movement, until the opposite working face —11— of the cam 10— encounters the other operating member or plunger —5—, the reverse action of the leaf-turner being accomplished by the depression of the last named plunger. Each leaf-turner is, therefore, associated with two operating manuals, each acting separately upon the crank-arm —10— to reverse the action of the leaf-turner, and at the same time, each leaf-turner may be actuated by its operating member —8— irrespective of the manuals —5—, or the arm —6— may be thrown from one extreme position to the other by direct engagement of the hand therewith.

Mounted upon the longitudinal center of the upper portion of the frame —1— is a leaf-holding finger —16—, which is pivoted upon and adjustable longitudinally of a fixed bolt or stud —17— on the upper portion of the frame 1—, the axial adjustment serving to permit the insertion of a greater or less number of sheets between the finger and frame, while the rotary or lateral adjustment permits said finger to be thrown out of engagement with the sheet to allow the latter to be more readily removed when desired. This finger is spring-pressed outwardly against an adjustable abutment or nut —18— by means of a spring —19—, so that in adjusting the finger for different numbers of sheets it is simply nec-

essary to adjust the nut by hand. A similar, but somewhat longer finger —20— is mounted upon a stud —21— at the lower longitudinal center of the frame —1—, and is adjustable axially of said stud in a manner similar to that described for the adjustment of the finger —16—, or by means of a nut —22—.

In operation, the leaves to be turned are inserted in the arms —6— which are disposed in their extreme position at one side before the playing is begun, and when it is desired to turn the sheet the operator quickly depresses the key —13— of the plunger which is engaged with the crank-arm —10—, whereupon the arm —6— is instantly thrown or turned to its other extreme position ready to be returned by the depression of the companion plunger, or if a slower turning movement is desired, it may be accomplished by turning the knobs —8— which operate the rock-shafts —4— independently of the manuals —5—.

What I claim is:

1. In a leaf turner a casing having a supporting rack extending therefrom, a rock shaft mounted for rotation in said casing and with a leaf supporting device extending laterally from one end and adapted to rest against said rack, said shaft having a laterally extending crank arm within said casing and provided with processes on its opposite faces, and spring actuated members having rounded terminals adapted to alternately engage with the processes on said crank arm, to cause the alternate operation of said shaft and the leaf support carried thereby.

2. In a leaf turner, a casing, a rock-shaft mounted for movement through said casing with a turning knob at one end and a leaf supporting device at the other end, a laterally extending crank arm connected to said shaft within the casing, and spring actuated manuals carried by said casing and adapted to alternately engage said laterally extending crank arm to cause the action of said leaf turning device.

In witness whereof we have hereunto set our hands this 25th day of August, 1906.

AUGUSTUS E. BEH.
ESTELLA BEH.
